UNITED STATES PATENT OFFICE.

HARRY P. DAVIS AND PAUL MACGAHAN, OF PITTSBURG, PENNSYLVANIA, ASSIGNEES TO
WESTINGHOUSE ELECTRIC & MANUFACTURING COMPANY, A CORPORATION OF PENN-
SYLVANIA.

INDICATING MEANS FOR INSTRUMENTS.

No. 920,927.

Specification of Letters Patent.

Patented May 11, 1909.

Application filed October 21, 1905. Serial No. 283,850.

To all whom it may concern:

Be it known that we, HARRY P. DAVIS and PAUL MACGAHAN, citizens of the United States, and residents of Pittsburg, in the county of Allegheny and State of Pennsylvania, have invented certain new and useful Improvements in Indicating Means for Instruments, of which the following is a specification.

10 Our invention relates to indicating means for instruments, and particularly to such means as may be applied to synchronism indicators.

15 The object of our invention is to provide an improved indicator for the purpose set forth which shall be inherently useful and which may be readily and advantageously combined with other parts.

In Patent No. 685,155, granted October 22d, 1901, to Paul M. Lincoln, is set forth and claimed a synchronism indicator comprising relatively movable members one of which is provided with a single winding that is adapted to be connected to one source of 25 alternating current and the other of which is provided with two windings that are adapted to be connected to another source of alternating current. Means are also provided for displacing the phase of the current in one of 30 the windings of the second member with respect to that in the other winding, and such means preferably comprises a non-inductive resistance that is connected in series with one of the windings and an inductance or choke- 35 coil that is connected in series with the other winding. For the non-inductive resistance which is connected in series with one of the windings of the second chamber, we propose to employ incandescent lamps, which serve 40 also as means for illuminating the dial of the instrument, and we further provide the indicating arm which is carried by the movable member with a lamp which is connected in series with the stationary lamps and one of 45 the windings of the second member.

Our invention is illustrated in the accompanying drawings, Figure 1 of which is a view, in front elevation, of an instrument constructed in accordance therewith, a portion of the front plate being broken away. Fig. 2 is a view, partially in side elevation and partially in section, of the instrument shown in Fig. 1, and Fig. 3 is a diagrammatic view of a system embodying our inven-

tion and illustrating the circuit connections 55 thereof.

The stationary magnetizable core 1 is provided with a winding 2 that is connected between distributing conductors 3 and 4 leading from a suitable source 5 of alternating current energy which is to be caused to operate synchronously with another suitable source 6 of alternating current energy. An annular magnetizable core 7 is rotatably mounted within the magnetic influence of the stationary core 1 and is provided with two windings that respectively comprise coils 10 and 11 and 12 and 13 which are disposed alternately upon the core 7. One terminal of each of the windings is connected to a slip-ring 14 and the remaining terminals are connected respectively to slip-rings 15 and 16. The slip-ring 14 is engaged by a brush 17 that is connected to distributing conductor 18 of the source 6. A brush 19 engages slip-ring 15 and is connected to one terminal of an inductance or choke-coil 20 the other terminal of which is connected to distributing conductor 21 of the source 6. Slip-ring 16 is engaged by a brush 22 which is connected to one terminal of each of lamps 23 and 24, the remaining terminals of which are connected to distributing conductor 21. The lamps 23 and 24 are supported from the back of the instrument casing 25 and at the rear of a suitable dial or indicator plate 26 that is composed, preferably, of glass or other transparent or translucent material and may bear any marks for indicating purposes that may be desired, such, for example, as that shown at 30 and the letters "S" and "E." The lamps 23 and 24 thus serve both as resistance in the circuit of the coils 10 and 13 and as illuminating means for the dial of the instrument.

The rotatable member is provided with an indicator arm 27 which carries, at its outer end, a lamp 28 that is connected between terminal 29 of coil 10 and slip-ring 16 and also serves as a non-inductive resistance in the circuit of the coils 10 and 13, as well as illuminating means for the indicator arm.

When it is desired to cause either of the sources 5 and 6 to operate in synchronism with the other source which is already in operation, the instrument is connected, as indicated in Fig. 3, with the sources by closing the switches 31 and 32. If the sources are

- exactly in synchronism when the switches are closed, the lamp 28 will occupy a position directly in the rear of the mark 30 on the dial-plate 26, but if the frequency of the machine 5 which is being synchronized with the one already in operation is less than that of the other, the arm 27 and the lamp 28 will be rotated in a clockwise direction. If the frequency of the machine to be synchronized 10 is greater than that of the machine already in operation, the lamp will rotate in a counter-clockwise direction. The speed of rotation of the indicator arm and the lamp will be proportional to the difference in frequency and 15 voltage of the two sources, so that, as the two sources approach synchronous operation, the pointer will decrease in speed and at synchronism will occupy a position directly in front of the mark 30.
- 20 It is of course understood that a single stationary lamp may be employed for illuminating the dial, or any other suitable number may be employed; that more than one lamp may be mounted upon the movable indicator 25 arm and that the lamp or lamps upon the indicator arm may be connected in circuit in any other suitable manner if it is not desired to utilize such lamp or lamps as additional resistance in the circuit of one of the windings of the movable member.

While it will generally be found most expedient to employ lamps as indicating means, it will be readily understood that any other indicating means may be mounted upon the 35 rotatable indicator arm which may or may not include inductive resistance to be connected in circuit with one of the windings of the movable member.

Other modifications of the details of construction and of the arrangements of the circuits may be employed without departing from the spirit of the invention.

As we are not aware that the movable arms or pointers of indicating instruments have 45 heretofore been provided with illuminating means, we have fully set forth such structure in the specification and covered it broadly in the appended claims.

We claim as our invention:

- 50 1. The combination with two sources of alternating current, and relatively movable members one of which is provided with a winding connected to one of the sources and

the other of which is provided with windings connected to the other source, of an indicator 55 arm operated by one of the members, a lamp carried by said arm and connected in the circuit of one of the windings of the second member, and stationary lamps also connected in the said circuit to serve as resistance and as illuminating means.

2. The combination with two sources of alternating current, and relatively movable members one of which is provided with a winding connected to one of the sources and 65 the other of which is provided with windings connected to the other source, of an indicator arm operated by one of the members, and a lamp carried thereby and connected in circuit with one of the windings of the second 70 member to serve as a resistance and as an indicator.

3. The combination with relatively movable members one of which is provided with a single magnetizing winding and the other 75 of which is provided with a plurality of such windings, of an indicator arm operated by one of the members, and a lamp carried thereby and connected in circuit with one of the windings of the second member to serve 80 as a resistance and as an illuminating means.

4. The combination with relatively movable members one of which is provided with a single magnetizing winding and the other of which is provided with a plurality of such 85 windings, of an indicator-dial, one or more lamps connected in circuit with one of the windings of the second member and serving both as resistance and as means for illuminating the dial, an indicator arm operated by 90 one of the members, and an illuminated indicator carried thereby and energized from the circuit of one of the windings of the second member.

In testimony whereof, we have hereunto 95 subscribed our names this 13th day of October, 1905.
